UNITED STATES PATENT OFFICE.

FRANK W. AYERS, OF PORTLAND, OREGON, ASSIGNOR OF ONE-HALF TO CHARLES C. FELT, OF PORTLAND, OREGON.

METALLIC-LETTER-CASTING MACHINE.

1,272,887.

Specification of Letters Patent. Patented July 16, 1918.

Application filed February 16, 1917. Serial No. 149,115.

To all whom it may concern:

Be it known that I, FRANK W. AYERS, a citizen of the United States, residing at Portland, in the county of Multnomah and

5 State of Oregon, have invented certain new and useful Improvements in Metallic-Letter-Casting Machines; and I do hereby declare the following to be a full, clear, and exact description of the invention, such as 10 will enable others skilled in the art to which it appertains to make and use the same.

The invention relates to a metallic letter casting machine.

Heretofore, the making of name plates for 15 lettering castings, has caused considerable annoyance, expense and delay in the making of patterns for the castings and has necessitated frequent tedious carving by hand and the use of expensive metallic letters.

20 The object of the present invention is to obviate these objections and to provide a simple, practical and efficient metallic letter casting machine adapted to be manufactured at a sufficiently low cost to place it 25 within reach of every pattern shop and capable of lessening the cost of lettering patterns and of enabling the material used in the manufacture of such metallic letters to be used again when the letters become worn.

30 A further object of the invention is to provide a metallic letter casting machine of this character which will enable metallic letters to be rapidly manufactured and equipped with means, after the letters have 35 been cast, of simultaneously compressing and shrinking the same to render the material of the letters compact and to increase the hardness of the letters and at the same time loosen the letters so that the same 40 may be readily discharged from the molds or dies.

Another object of the invention is to provide an automatically operating device adapted to knock or jar the cast letters from 45 the molds or die plates should they not fall from the plates by an inverting of the same through the operation of the machine.

With these and other objects in view, the 50 invention consists in the construction and novel combination of parts hereinafter fully described, illustrated in the accompanying drawings and pointed out in the claims here- 55 to appended; it being understood that various changes in the form, proportion, size and minor details of construction, within

the scope of the claims, may be resorted to without departing from the spirit or sacrificing any of the advantages of the invention.

In the drawings:

Figure 1 is a plan view of a metallic letter casting machine constructed in accordance with this invention.

Fig. 2 is a side elevation of the same.

Fig. 3 is an end elevation of the metallic letter casting machine.

Fig. 4, is a longitudinal sectional view of the same.

Fig. 5 is a transverse sectional view thereof.

Fig. 6 is an enlarged detail sectional view of a portion of one of the sprocket wheels and the sprocket chain or carrier illustrating the arrangement of the mold plate.

Fig. 7 is a detail vertical sectional view on the line 7—7 of Fig. 2.

Fig. 8 is a detail horizontal sectional view on the line 8—8 of Fig. 2.

Figs. 9 and 10 are detail views of the links of the chain or conveyer.

Fig. 11 is a detail view of one of the mold plates.

Fig. 12 is an enlarged detail view illustrating the construction of the letter ejecting device.

Fig. 13 is a detail side view of one of the links.

Fig. 14 is a detail view of one of the mold plates showing the casting face thereof.

Like numerals of reference designate corresponding parts in the several figures of the drawings.

In the accompanying drawings in which is illustrated the preferred embodiment of the invention the metallic letter casting machine comprises in its construction a frame or casing 1 preferably consisting of a casting of any suitable material and composed of integral side and end walls and a top 2, but the frame or casing may be of any other desired construction as will be readily understood. The side and end walls are provided at their lower edges with attaching lugs or ears to enable them to be readily secured to a suitable support and the end walls are provided with oblong openings 3 to enable sprocket wheels 4 to be readily introduced into the frame or casing which is preferably tapered upwardly, as shown.

The sprocket wheels 4, which have polyg-

onal rims 5, are mounted on transverse shafts 6 and 7, the shaft 7 being adjustable inwardly and outwardly with relation to the shaft 6 to enable the sprocket chain or conveyer to be placed under the desired tension. This inward and outward horizontal adjustment of the transverse shaft 7 is preferably effected by means of inner and outer adjustable plates 8 and 9 and adjusting screws 10 located at opposite sides of the frame or casing of the machine. The side walls of the frame or casing are provided with longitudinally disposed horizontal slots 11 for the reception of the terminal portions of the transverse shaft 7, and they are also provided with spaced horizontal exteriorly arranged guiding flanges 12 disposed in pairs and receiving the outer plates, as clearly illustrated in Fig. 7 of the drawings. The outer plates are enlarged to form bosses around the shaft and they are connected with the inner plates by screws 13, which are adapted to draw the plates in clamping relation to maintain them firmly in engagement with the side walls after the shaft 7 has been properly set or adjusted. The screws 10, which are mounted in lugs 14 of the side walls of the frame, engage threaded openings 15 of flanges 16 formed integral with the outer plates and located at the outer ends thereof. By adjusting the screws the conveyer or sprocket chain may be arranged at the proper tension. The shafts are journaled in the bearings 35 and are maintained against longitudinal movement by set collars 17. One of the shafts is extended and equipped with a crank 18, or other suitable device, for rotating the shaft to operate the machine.

40 The polygonal rims of the sprocket wheels are provided at their angles with transverse grooves 19 for the reception of hinge joints 20 of links 21 of the endless sprocket or conveyer chain, which carries mold plates 22. The mold plates for casting the letters may be constructed for casting one or more letters or other characters of any style or form and they are interlocked with the links by means of corner lugs 23 and are maintained 45 in their interlocked relation by studs 24 and nuts 25. The links are provided with central bosses 26 through which the threaded studs 24 pass and the nuts engage the links at the inner faces thereof and are received 50 in openings 27 of the rims of the sprocket wheels. The polygonal faces of the rims of the sprocket wheels are substantially coincident with the links of the conveyer or sprocket chain and the latter is interlocked 55 with the sprocket wheels and is actuated when the crank 18 is turned to rotate the shaft on which it is mounted.

60 The upper flight or stretch of the conveyer chain travels over the top of the frame or casing, which is provided with a central lon-

gitudinal groove 28 to receive the hinge joints of the links. The chain also travels beneath an opening or outlet 29 of a bowl consisting of inner and outer shells 30 and 31 formed integral with each other and connected at the bottom of the bowl at the said outlet or opening 29. The bowl is provided at the bottom with attaching flanges 32 and is bolted or otherwise secured to the top of the frame or casing. The inner shell which 70 contains the material from which the letters are cast terminates short of the plane of the upper edges of the outer shell which is equipped with a pivoted cover 32 adapted to be swung horizontally on its pivot 34 to 75 cover and uncover the bowl and it is provided at a point diametrically opposite the pivot with a suitable handle 35. The outer shell is provided at one side with an opening 36 into which extends the burner 37 of a gasolene torch 38 and the latter is arranged upon a supporting bracket 39 adjustably secured to the adjacent side of the frame or casing by a bolt 40 operating in a vertical slot 41 and provided with a nut 42. The 80 slotted portion of the frame or casing is arranged in a vertical plane and the bolt is preferably cast in the bracket and a washer 43 is interposed between the nut and the inner face of the slotted portion of the frame 85 or casing. The bracket, which may be of any desired construction, is adjustable vertically to accommodate torches or other heating devices of various sizes and the inner bowl is thickened at 44 opposite the opening 90 36 where the flame of the torch impinges against the inner shell or bowl proper. The flame is adapted to spread in the intervening space 45 between the inner and outer shells and the heated air is adapted to escape 95 through an opening 46 formed in the outer shell at the bottom thereof and communicating with an outlet passage 47 extending longitudinally of the top of the frame or casing and around the front end of the same 100 and terminating at approximately the plane of the horizontal center of the adjacent sprocket wheel, but the length of the outlet passage, which is formed in the top and end of the frame or casing, may be varied as will 105 be readily understood.

The upper flight of the conveyer or sprocket chain travels in the direction of the arrow in Fig. 4 of the drawings, and while the chain preferably consists of 26 links to 110 correspond with the number of letters of the alphabet, it may of course be of any desired length and contain any desired number of links which successively carry their mold plates beneath the outlet of the inner bowl 115 to cause the mold cavities of the mold plates to become filled with the melted or molten material within the bowl and the molded letters or characters are sheared off smooth at the upper faces of the mold plates by a 120

steel plate or blade 49 mounted in the bottom portion of the bowl in a recess at the rear wall of the outlet.

The cast material contained within the 5 mold plates is hardened or compressed to harden the letters and render the material more compact by means of a roller 50 located in rear of the bowl and mounted in a suitable casing 51 with which is connected a 10 weighted arm or lever 52. The roller, which in practice is designed to be maintained in a cool condition by cold water or other suitable means, chills the cast letters or other characters and causes the same to shrink sufficiently to permit the contents of the molds 15 to be readily discharged when the mold plates are inverted in passing around the sprocket wheel at the rear or discharge end of the machine. The casing 51, which is 20 pivoted by a pin 53 or other suitable fastening device between spaced ears or flanges of the outer shell of the bowl, is preferably composed of spaced sides and a connecting portion to which the arm 52 is riveted or 25 otherwise secured, and the said arm carries a weight 54 which is adjustable inwardly and outwardly to vary the pressure exerted by the roller upon the cast letters or characters. The casing and the arm and the 30 weight constitute a weighted lever for pressing the roller downwardly upon the mold plates.

In order to insure a proper discharge of the contents of the mold plates an ejecting 35 device is employed. The ejecting device consists of a bell crank lever 55 pivoted at its angle on a horizontal pin or pivot 56 on which is also mounted a coiled spring 57 having one end connected with the frame by 40 a suitable fastening device 58 and connected at its other end with one arm of the bell crank lever. One of the arms of the bell crank lever extends upwardly and is arranged in the path of lugs 59 carried by the 45 rear sprocket wheel and arranged to successively engage the upwardly extending arm of the bell crank lever. When a lug strikes the upwardly extending arm of the ejecting lever the other arm which extends 50 inwardly in a slightly inclined position is swung downwardly against the action of the coiled spring which when the lug releases the upwardly extending arm causes the longitudinal arm to be swung upwardly into 55 contact with the adjacent mold plate and the blow is adapted to jar and cause the discharge of a letter or character should the same not have been previously discharged by the inverting of the mold plate. The 60 longitudinally disposed arm is provided at its terminal with an upwardly projecting portion or head 60.

The base portion 61 of the bowl forms a longitudinal groove or way for the passage 65 of the upper flight or run of the sprocket

or conveyer chain and presents a flat upper face to the mold plates and straight vertical side edges to the side edges of the links, which are held against movement out of their true path so that an accurate casting 70 of the letters or characters is assured. Also the grooves or recesses which accommodate the hinge joints of the links terminate short of the side edges of the rims of the sprocket wheels so that the chain is held against lateral movement as well as longitudinal creeping 75 on the wheels.

The mold plates are interchangeable and letters and characters of various kinds and 80 styles may be employed and after the material from which the letters or characters are to be molded has been heated to the desired temperature and is in the proper condition the machine may be rapidly operated by turning the crank, but instead of operating 85 the machine by hand any other suitable means may of course be employed, and the letters or characters may be rapidly and accurately cast. The outlet passage for the hot air, besides affording a circulation and 90 draft for the flame from the burner to permit the latter to envelop the inner shell, also enables the hot air to take any chill off the molds prior to the same passing beneath the bowl and the said molds will be in a heated 95 condition when they receive the molten material at the outlet of the bowl. Also the reinforcing enlargement of the inner shell presents a convex face to the flame and tends to facilitate the spreading of the flame of 100 the burner over the outer surface of the inner shell.

What is claimed is:

1. A metallic letter casting machine including a bowl provided at the bottom with 105 a centrally arranged outlet, said bowl being composed of inner and outer shells connected together at the said outlet centrally of the bottom and being spaced apart from the bottom to the top to provide an uninterrupted 110 open intervening space, extending entirely around the bowl and beneath the bottom thereof, said outer shell being provided at one side with an opening, heating means located at the said opening for heating the 115 contents of the inner shell, and a conveyer provided with molds arranged to pass beneath the said outlet.

2. A metallic letter casting machine including a bowl or receptacle having an outlet, polygonal sprocket wheels spaced from the outlet and having grooves or recesses at the angles, an endless chain having a flight extending beneath the outlet, said chain being composed of links having hinge joints 120 received within the said recesses, and mold plates provided with means for securing them to the links and having corner lugs interlocked with the said links. 125

3. A metallic letter casting machine in- 130

cluding a bowl or receptacle having an outlet, polygonal sprocket wheels having grooves or recesses at the angles and provided with openings located at points between the said angles, an endless chain composed of links having hinge joints received within the said recesses, and mold plates provided with centrally arranged studs secured to the links and adapted to project into said openings, said mold plates being also provided with corner lugs interlocked with the links.

4. A metallic letter casting machine including a superimposed bowl or receptacle having an outlet, a frame or casing supporting the bowl or receptacle and provided with opposite slots, transverse shafts, one of the said shafts extending through the said slots, sprocket wheels mounted on the said shafts, an endless sprocket chain arranged on the sprocket wheels and having molds adapted to be carried to and from the outlet of the bowl by the said chain, and means for adjusting the chain for maintaining the same at the proper tension, said means comprising inner and outer plates having bearing openings receiving one of the said shafts, fastening means connecting the said plates, and adjusting screws for moving the said plates inwardly and outwardly.

5. A metallic letter casting machine including a bowl or receptacle having an outlet, a conveyer provided with molds and adapted to carry the same to and from the said outlet, and a weighted lever provided with a roller arranged to engage the cast material after the same leaves the bowl.

6. A metallic letter casting machine including vertical sprocket wheels, a conveyer

chain arranged on the sprocket wheels and having upper and lower horizontal flights and provided with molds, means for supplying material to the said molds, and an ejecting device comprising an angle lever pivoted below the lower flight, a spring for urging the angle lever in one direction, and lugs carried by one of the sprocket wheels and arranged to engage and release the said lever, one arm of the lever being arranged to engage the said molds of the bottom flight.

7. A metallic letter casting machine including a frame or casing having a longitudinally disposed hot air outlet constituting a draft passage, a superimposed bowl composed of spaced inner and outer shells and having an opening communicating with the space between the shells and the said passage, the inner shell being provided with an outlet, and a conveyer having molds arranged to pass beneath the outlet of the inner shell and along the said passage whereby the chill is removed from the molds.

8. A metallic letter casting machine including a frame or casing provided with an outlet passage and having a vertical guide or way at the inner end thereof, a superimposed bowl mounted upon the frame or casing and composed of spaced inner and outer shells and having an outlet communicating with the said space and with the said passage, the said bowl being adjustable in the guide or way.

In testimony whereof I affix my signature in presence of two witnesses.

FRANK W. AYERS.
